UNITED STATES PATENT OFFICE.

JAMES L. CONNOR, OF SAN JOSE, CALIFORNIA.

RECLINING FRAME.

Application filed September 27, 1923. Serial No. 665,179.

It is one object of my invention to provide an adjustable back mounted on a frame that can be readily placed on a bed or other suitable surface, and preferably having a table or tray member removably attached thereto.

In some forms of physical afflictions the patient must sleep in a half-reclining posture, and I contemplate providing a device 10 in which the back can be quickly and easily adjusted at the required angle according to the desire of the patient. I also contemplate providing a device that can be used by aged persons and others on lawns, 15 beaches and beds where an adjustable back and a lunch or work table are both desired.

It is still another object of my invention to provide a device of the character indicated in which the tray is provided with 20 arms slidably engaging the back whereby to permit adjustment of the back without materially disturbing the horizontal arrangement of the tray.

It is still another object of the invention 25 to provide a device in which the tray is adjustable relative to the back so that its spacing therefrom may be varied at will.

In the drawings:—

Figure 1 is a side elevation of the device.

Figure 2 is a plan view of the same.

Figure 3 is a section on line 3—3 of Figure 1.

Referring more particularly to the drawing, 30 1 indicated a base frame comprising a rear cross piece and two parallel forwardly extending side pieces. Adjacent to the base piece and secured to the inner sides of the two side pieces are rack members 2. At 3 is a bar extending transversely of the frame and secured to side members 1 thereby making the frame rigid and providing a mounting for back 4 which is attached thereto by means of hinges 5.

At 6 I show a bail engaging rack members 2 and pivotally connected to the rear of back 4 by staples 7. Guide elements are mounted on opposite edges of back 4 as shown at 8.

At 9 I show a tray provided with side extensions 10 forming arms and adapted to pass freely through their respective guides 8. Tray 9 has legs 11 pivotally mounted thereon as shown by means of hinges as at 12, each leg having a pin 13

formed on its lower end adapted to engage orifices 14 in the outer ends of side members 1. On the outer sides of side members 1 are placed eyes 15, and on the lower outer sides of legs 11 are mounted hooks 16 adapted to engage eyes 15.

The device is assembled as shown and set upon a bed or any other suitable surface, the angle between members 1 and legs 11 being greater than a right angle so that 65 the depression of the rear part of the device through the placing of the weight of the occupant of the device on back 4 will place the tray 9 in a substantially horizontal position.

In this construction the back 4 may be readily adjusted at any desired angle without materially disturbing the level of the tray, and the tray may be placed to accommodate a person of any size or at a 75 convenient distance from the occupant's body. When not in use the hooks 16 are unfastened and the tray lifted off, the legs folding up against its under side as shown in dotted lines in Figure 3. The back 4 is now folded over on frame 1 and the device may be stored or packed in a small flat package.

From the foregoing it may be seen that I have provided a device that is simple in 85 form and construction, economical to manufacture, easily assembled and disassembled and highly efficient in its practical application.

It is to be understood, of course, that 90 while I have herein shown and described one specific embodiment of my invention, changes in form, construction and method of operation may be made within the scope of the appended claim.

I claim:—

A device of the character described, consisting of a base frame including parallel side members, a back pivotally mounted thereon, means for adjusting the back relative to said frame, guide elements extending from the sides of said back to form guide slots, a tray, arms carried by said tray and having free slidable engagement with said slots, legs rigidly mounted on said tray, and means for rigidly and removably mounting said legs upon said side members at varying distances from said back.

JAMES L. CONNOR.
